PREPARATION OF CHLORINE PENTAFLUORIDE
 Frank C. Gunderloy, Jr., Woodland Hills, Walter Maya,
 Los Angeles, and Richard D. Wilson, Canoga Park,
 Calif., assignors to North American Aviation, Inc.
 No Drawing. Filed Sept. 17, 1963, Ser. No. 310,970
 4 Claims. (Cl. 23—205)

This invention relates to a process for preparation of chlorine pentafluoride (ClF_5) by reaction of fluorine with tetrafluorochlorates of certain alkali metals.

A method for the preparation of ClF_5 by subjecting a mixture of fluorine and chlorine, for example, to a glow discharge is described in patent application, Ser. No. 253,521, filed Jan. 21, 1963, by Walter Maya and Hans F. Bauer. As therein mentioned, ClF_5 is an extremely high-energy oxidizer of greater oxidizing potential than chlorine trifluoride which finds utility as an oxidizer for rocket propellant fuels. The boiling point of ClF_5 is about -14°C .

By the above-mentioned glow discharge process, the yields of ClF_5 are relatively low and various resultants are produced requiring cryogenic fractionation for separation, whereas according to the process of the instant invention only one condensable gaseous resultant (ClF_5) is produced.

There are three known alkali metal tetrafluorochlorates, they being the potassium, cesium and rubidium species. Lithium and sodium tetrofluorochlorates are not known to have been produced. The reactions of the process of this invention may be represented by the equation:

wherein M is an alkali metal of the group consisting of potassium, cesium and rubidium.

Each of the potassium, cesium and rubidium tetrafluorochlorates may be prepared according to either of two known processes, i.e., by condensing chlorine trifluoride upon the alkali metal fluoride and by chlorinating the alkali metal fluoride.

The invention is hereinafter illustrated in greater detail by description in connection with the following specific examples of the practice of it.

EXAMPLE 1

0.1 mole (15.2 g.) of cesium fluoride was placed in a 150 ml. stainless steel bomb and 0.13 mole (3,000 cc.) of

2

chlorine trifluoride was condensed into the bomb with cooling of the bomb in a bath of liquid nitrogen. The bomb was then heated to 80°C . for 4 hours and was then evacuated through a -196°C . trap for collecting the unreacted ClF_3 which was measured and found to be about 0.04 mole. 4,000 cc. of fluorine were then condensed into the bomb and the contents of the bomb was maintained at about 80°C . for six hours, the initial pressure in the bomb being about 520 p.s.i.

The bomb was then immersed in a bath of liquid nitrogen and the excess fluorine was pumped off. The bomb was connected to a train of traps at temperatures not above -112°C ., and the liquid nitrogen bath was removed from the bomb. A total of 0.04 gram (.003 mole) of ClF_5 was found in the traps along with traces only of impurities, e.g., FCIO_2 and ClO_2 . The yield of ClF_5 was calculated to be 0.33 percent on the basis of the amount (0.09 mole) of ClF_3 which reacted with the cesium fluoride, which basis has its equivalent in terms of cesium tetrafluorochlorate initially formed and thereafter fluorinated.

EXAMPLE 2

0.1 mole (5.8 g.) of potassium fluoride was placed in a 150 ml. stainless steel bomb containing small nickel rods and 0.13 mole (3,000 cc.) chlorine trifluoride was condensed into the bomb. The bomb was rotated overnight at room temperature. Thereafter the excess (about 0.08 mole) ClF_3 was removed, showing the KF reacted with the ClF_3 in a ratio of 1 to .5, thus indicating that the tetrafluorochlorate was a double salt, represented as

4,000 cc. of fluorine were then condensed into the bomb. The bomb was maintained at about 200°C . for about 27 hours, the initial pressure in the bomb at 200°C . being about 800 p.s.i. A total of 0.39 gram of ClF_5 was recovered and the yield was calculated to be 6 percent.

EXAMPLE 3

40 The same technique as that described in Example 2 was followed, using rubidium fluoride in the place of potassium fluoride and 5.3 percent yield of ClF_5 was recovered.

EXAMPLES 4-26

45 The same technique as that described in Example 2 was followed for the examples contained in Tables I and II.

TABLE I.—FLUORINATION OF POTASSIUM TETRAFLUOROCHLORATE

Example No.	KClF ₄ ·KF in moles	Fluorine in liters	Initial Pressure in p.s.i.	Temp., °C.	Time, Hours	ClF ₅ , percent yield
4	(Note a)	4	600	150	234	3
5	0.1 (note b)	4	600	142	24	6
6	(Note c)	4	600	150	20	11
7	0.1	4	800	300	8	25
8	(Note c)	8	1,200	140	16	11
9	0.1	4	520	80	150	2.5
10	0.1	2	180	250	140	2.5
11	(Note c)	12	1,000	200	95	10
12	0.1	3	150	150	116	2.5

See Notes at end of Table II.

TABLE II.—FLUORINATION OF CESIUM TETRAFLUOROCHLORATE

Example No.	CsClF in moles	Fluorine in liters	Initial Pressure in p.s.i.	Temp., ° C.	Time, Hours	ClF ₅ , percent yield
13	(Note d)	4	600	135	6	9
14	(Note c)	4	620	150	4	5
15	0.1	4	600	150	24	30
16	(Note c)	4	600	150	20	20
17	(Note c)	4	600	142	24	2
18	0.5	22	900	126	60	25
19	(Note c)	18	790	130	20	30
20	(Note c)	15	660	132	19	3
21	0.5	18	790	130	20	35
22	(Note c)	15	660	132	19	15
23	(Note e)	15	660	150	22	40
24	(Note e)	15	660	150	234	44
25	(Note e)	15	660	150	116	31
26	(Note e)	15	660	150	24	8.5

Note a—Example 4 was performed by fluorinating the contents of the bomb following completion of Example 2 without regeneration with ClF₅.

Note b—For Examples 5 and 6 the bomb contained 0.1 mole NaF mixed with the KF.

Note c—For each Example marked with "note c", the contents of the bomb used in its next preceding example were regenerated with ClF₅.

Note d—Example 13 was performed using the contents of the bomb following Example 1 and regenerating with ClF₅.

Note e—Example 23 was performed by fluorinating the contents of the bomb following completion of Example 22 without regeneration with ClF₅.

The chemical action or speed of chemical change involved in the reactions of the process of this invention is affected, as is usual for chemical reactions, by the factor of temperature at which the reactions are run. The above examples show generally that an increase in temperature of the reactants results in an increase in the yield of ClF₅. Performing the reactions of this invention at a temperature or at temperatures in the range of from room temperature to about 80° C. is impractical from a commercial standpoint because the yields are low. For an upper limit of temperature as a factor affecting the process of this invention, the temperature of about 300° C. is selected because above that temperature severe corrosion of the containers results.

With respect to the matter of concentrations of the reactants, inert gasses, e.g., nitrogen and helium, may be present in the reaction zone without affecting the qualitative aspects of the reactions of this invention. Obviously such contaminants which through combination with fluorine form corrosive products should be avoided. When it is desired to obtain the pure ClF₅, purity of the two reactants avoids the need for separating the desired product from contaminants.

The tetrafluorochlorates are solids while the other reactant, fluorine, is a gas, and through the reaction between them resulting in the formation of ClF₅ occurs immediately upon bringing the reactants together, the fact that one of the reactants is in the solid phase makes it desirable from a practical standpoint that the tetrafluorochlorates be agitated throughout the time allowed for the reaction to run.

It is apparent from the above examples that changes in pressure are without effect on the reactions of this invention except insofar as pressure determines effective concentration of the fluorine gas. In the above examples 150 p.s.i. was the minimum pressure utilized, but such mini-

mum pressure was prescribed only because of the size of the apparatus employed, making it necessary that the fluorine be under pressure in order to provide a sufficient number of fluorine atoms for measurable reactions to occur.

It will be understood that it is intended to cover all changes and modifications of the examples of the invention herein chosen for the purposes of this disclosure, which do not constitute departures from the spirit and scope of the invention.

Having described the invention, what is claimed is:

1. A process for preparing chlorine pentafluoride comprising the steps of reacting fluorine with at least one tetrafluorochlorate of an alkali metal of the group consisting of potassium, cesium and rubidium, and collecting chlorine pentafluoride.

2. The process of claim 1 in which the reaction is run at a temperature in the range of from 80° to 300° C.

3. The process of claim 2 in which the reaction is run at a pressure of at least 150 p.s.i.

4. A process for preparing chlorine pentafluoride comprising the steps of reacting at least one fluoride of the group consisting of potassium, cesium and rubidium fluoride with chlorine trifluoride, and thereafter subjecting the products of said reaction to reaction with gaseous fluorine, and collecting the chlorine pentafluoride evolved.
